INTERNAL COMBUSTION ENGINE

Alexander Ragan, Jr., Baltimore, Md.

Application July 26, 1932, Serial No. 624,802

2 Claims. (Cl. 64—25)

This invention relates to internal combustion engines and has particular relation to a device for controlling the functions of the valve mechanism of a four-cycle engine and the time when these functions take place in the cycle of the piston.

It is well known that the setting of the valve cycle of an internal combustion engine relative to the cycle of the piston of that engine controls to a great extent the performance of the engine. It is equally well known that the setting of the spark with relation to other portions of the cycle of the engine as a whole is very important and means have been provided to regulate the spark setting—both manually and automatically—as set forth in many patents.

The present practice is to set the valves at an arbitrary setting, far in advance of the piston as in the case of high speed motors. The particular valve setting is selected which, while a compromise, will give the best all-round performance. Since most motors are occasionally used at high speed, it is necessary for the valve setting to be far enough in advance to be effective at the desired high speed. But since most of the operation, particularly in automotive engines is at low and intermediate speeds, it is evident that the engine is operating at low torque and low efficiency during most of the time. The same condition is also present when the engine is operating at speeds exceeding the speed which corresponds to the setting of the valve mechanism.

The primary object of this invention is the provision of a means for controlling the position of the valve cycle with relation to the piston cycle of an internal combustion engine, so that a maximum torque may be obtained at all possible speeds.

Another object of the invention is the provision of means for automatically controlling the position of the valves in the engine cycle, the position to be varied automatically so as to obtain the greatest torque for that particular speed.

Still another object of the invention is the provision of a device which will control the time of the valve functions in the engine cycle and which is susceptible of slight modification to produce the desired results for the particular type of engine to which it is applied.

Other and further objects will be apparent to those skilled in the art from a reading of the complete specification and claims.

Referring to the drawing, the figure illustrates a front view of the invention as applied to the

forward end of an automotive four-cycle motor.

In the drawing 10 designates the crank shaft of a four-cycle engine and 11 a spur gear which is keyed thereto and driven thereby. In mesh with the gear 11 is a gear 12 which is mounted about and relatively rotatable to the shaft 13 which is the valve-controlling part of the motor. The shaft 13 is provided with a friction reducing bearing 14, upon which the gear 12 may rotate.

Keyed to the shaft 13 is a spider 15 having 10 arms 16. Cam-bearing face plates 17 are provided on the arms 16 to provide bearing surfaces for the cams to be described. Mounted on the gear 12 are centrifugally controlled cam members which will now be described. The pivots 18 are mounted on the body of the gear 12. These pivots 18 have mounted thereabout, centrifugal cam members 19 which are provided with cam portions 19^a in position to engage the cam bearing face plates 17.

The cam bearing face plates 17 have faces 17^a which contact with the cam faces 19^b of the cam portions 19^a. On the opposite side of the pivots 18 from the cam portions 19^a are weighted portions 19^c. These weighted portions 19^c have 25 a tendency to swing outwardly when the gear 12 is rotated. This tendency to fly outwardly is resisted by springs 20 which are secured at their fixed ends to the pivot 18 and at their opposite ends to the weighted portions as by the pins 21. 30

It will be noted from the direction of rotation of the gear 12 and the shaft 13, that the cam faces 19^b and the faces 17^a of the respective face plates 17, will be in contact with each other under normal rotative movement. However, in order 35 to insure constant contact between these surfaces, there may be provided one or more springs 22 which are secured at one end to pins 22^a which are mounted on the gear 12 and at the other end to the pins 22^b mounted on the arms 16. 40

In operation, the crank shaft 10 carrying the gear 11 drives the gear 12 which in turn drives the spider 15 through contact between the spider arms 16 and the cam portions 19^a. At the beginning of the rotative movement, as when the 45 engine is started, the centrifugal force throws the weighted portions 19^c outwardly, rotating about the pivots 18 as centers. This causes co-action between the cam faces and gives a relative rotation between the gear 12 and the shaft 50 13. As this rotation takes place, it will be clear that a change in the setting of the valves will be made in accordance with the speed of rotation of the gear 12. A greater speed of rotation of the gear 12 causes a greater swinging outwardly 55

of the weighted portions 19 with a consequent relative advance movement of the spider 15 relative to the gear 12.

This causes an advance or lead in the performance of all functions of the valves and any other devices connected to the shaft 13—as the ignition, for example.

When the centrifugal force for any particular speed of rotation, balances the force of the spring 10 20, the relative position of the spider 15 and the gear 12 will be maintained. When, however, there is change of the speed of rotation, there will be a change in position of the weighted portions 19^c, causing a change in the relative angular positions of the gear 12 and the spider 15. As soon as the rotation of the shaft 10 is again stabilized at a new speed, the parts will maintain their relative positions.

During operation and at rest, the springs 22 20 hold the faces 17^a and 19^b in contact with each other ready for coaction therebetween to cause a new setting of the valves.

While I have illustrated and described in detail an embodiment of my invention, I desire 25 to have it understood that this is merely illustrative and that modifications and changes may be made without departing from the spirit of the invention and within the scope of the appended claims.

30 Having described my invention what I claim and desire to secure by Letters Patent is:

1. In an internal combustion engine having a

crank shaft and a valve-controlling shaft, the combination of a gear on the crank shaft, a gear mounted about the cam shaft but rotatable relatively thereabout, a plurality of circumferentially spaced centrifugally operated cams, arms extending from and secured to the valve controlled shaft and having substantially radially extending flat faces coacting with the cams, the contacting points between the cams and arms being outwardly of the rotating centers of the 10 cams, and resilient tension members normally tending to hold the cam contacting faces and cams together.

2. In an internal combustion engine having a crank shaft and a valve-controlling shaft, the 15 combination of a series of radiating arms connected to the valve-controlling shaft, a gear mounted on the valve-controlling shaft and having circular bearing means therebetween, a series of centrifugally operated cams having substantially radially extending flat cam faces in contact with the respective arms and so constructed as to contact at different points on the cam and at different points on the arms, the contacting points between the cams and arms being outwardly of the rotating centers of the cams, resilient means for resisting the centrifugal movement of the cams and resilient means for holding the cams and arms in contact with each other.

ALEXANDER RAGAN, JR.
